UNITED STATES PATENT OFFICE.

FRANK A. BORST, OF SOUTH BEND, INDIANA, ASSIGNOR TO IDEAL CONCRETE MACHINERY COMPANY, OF SOUTH BEND, INDIANA, A CORPORATION OF INDIANA.

CONCRETE-MIXER.

No. 853,523.

Specification of Letters Patent.

Patented May 14, 1907.

Application filed December 28, 1906. Serial No. 346,798.

To all whom it may concern.

Be it known that I, FRANK A. BORST, a citizen of the United States, and a resident of the city of South Bend, in the county of St. Joseph and State of Indiana, have invented a new and Improved Concrete-Mixer, of which the following is a specification.

My invention relates to mechanical means for thoroughly mixing various substances, particularly the materials that are used to make concrete; and the objects of my improvements are,—to provide means of this kind in which the materials can be first mixed in the dry state and afterward in the presence of water; and to provide a drum mixer in which the materials can be thoroughly mixed and from which it can be discharged through openings in the drum on rotating the same in the reverse direction.

My invention further consists in the forming of the spiral sections of the drum so that the materials will be caused to converge and then be separated.

In the accompanying drawings, Figure 1 is an end view of the complete machine. Fig. 2 is a plan of the same. Fig. 3 is a cross section on the line A—A of Fig. 2. Fig. 4 is a detail of the screw of the second mixer. Fig. 5 is an end view of the screw mixer. Fig. 6 is a side view of the same.

Similar reference characters refer to like parts throughout the several views.

It is often desirable to mix concrete in batches, and also to first mix the materials dry and then mix them again after adding water. In the accompanying drawings, I have shown my improved mixer which consists of a novel drum mixer mounted so that it can discharge into a screw mixer, means being provided whereby water may be added to the mixed materials while they are moved along by the screw.

The frame of this machine consists of the stringers 1, the uprights 2 and 3, the cross pieces 4, 5, 6, 7, 8, and 9 and connecting pieces 10, and is braced wherever necessary. The cross piece 9 is a part of a portion of the frame which projects rearwardly from the cross piece 4 of the main frame. Any other desirable style of frame may be employed.

Mounted on the cross piece 6 is a yoke 71 carrying bearing wheels 12 which run in the groove 13 of the bearing ring 14 at one end of the drum. On the cross pieces 4 and 9 are

bearings 15 for the stub shaft 16 which is rigid with the flange or disk 17 at the other end of the drum. Between the two heads 19 of the drum extend a series of buckets 20 which convex outward and are formed generally spiral in cross section as shown in Fig. 3, and are made up of flat sections. This is partly because of ease in manufacture, but especially because the angular form of these buckets aids in the mixing. The side edges 21 of the buckets are flanged outwardly (indicated by dotted lines, Fig. 3) which flanges are attached to the heads 19. The inner edges of the buckets are turned in to form flanges 22 which materially aid in the mixing.

The chute 23 extends into the central opening of the drum and through it the material is dumped into the machine. While the machine is turning to the right (Figs. 1 and 3) the material will roll around over and through itself, especially converging to the middle on account of the conical construction of the buckets, which prevents the different materials from remaining in parallel bands around the inside of the drum. When the motion of the drum is reversed, (turning to the left, Fig. 3) the material will slide out along the buckets and discharge through the openings between the outer edge of each and the next adjacent, following bucket.

The bevel gear 18 on the end of the driving shaft 25 meshes with the gears 24 and 26 on the shaft 16. The driving shaft 25 has a pulley 28 mounted on its outer end, but any other desirable means for transmitting power to this shaft may be employed.

The gears 24 and 26 are loosely mounted on the stub shaft 16 and are caused to revolve in opposite directions by the gear 18. A clutch sleeve 27 having a groove to engage the key 29 in the shaft 16 will cause the shaft to revolve with gear 24 or 26, depending upon whether the jaws of the sleeve engage the jaws on the gear 24 or 26. The sleeve has a ring 30 which is engaged by the lever 31 to shift the clutch sleeve in the usual manner. This system of gears to change the direction of revolution of the drum is well known and any other desirable system may be employed. By swinging the lever 31, the drum may be caused to revolve in either direction, or it may be stopped by moving the lever to a central position.

Attached to the hub of the bevel gear 24

is the sprocket wheel 32 for driving the screw mixer. As this bevel gear revolves in but one direction, the screw of the mixer will turn in a constant direction.

- 5 The trough 38 of the screw mixer is supported by saddles 39, carried by the frame. The trough is provided with wings or aprons 40 and 41 to catch the material as it is discharged from the drum. The shaft 42 extends through the bearing 43 carried by the cross piece 5, and beyond the bearing is the sprocket wheel 44 which is connected to the driving sprocket wheel 32 by means of the chain 45.
- 15 The opposite end of the shaft 42 extends through the bearing 46 carried by the cross bar 47 which is mounted on the rods 48 of the brackets 49. The springs 50 normally hold down this cross bar, but should any gravel or piece of stone get wedged under a screw blade, the end of the shaft can rise and relieve the strain. The brackets are secured to the end saddle 39 and cross bar 8.

The major portion of the screw shaft is 25 square, and the blades 58 are provided with slots 57 so that they may be adjustably secured to the shaft by means of the bolts 56. As the position of the blades is such that the blade succeeding in pitch precedes longitudinally, the material is well mixed in its passage toward the discharge opening 55.

A water tank 54 having discharge pipe 53 may be mounted at any convenient location. The chute 23 is provided with a slide gate or 35 valve 55 of any desired form which is adapted to control the passage of the materials into the drum mixer.

The materials for a "batch" of concrete 40 is dumped into the chute 23 and slides down into the drum where it is well mixed. When the mixing has been completed, the lever 31 is swung over, and, the drum's movement being reversed, the material is dumped onto the screw of the lower mixer. Water is permitted to flow onto the material after the 45 screw has moved it from under the drum mixer. As soon as the "batch" has passed from the chute 23 into the mixer, the gate

55 is pushed in, permitting a second "batch" to be dumped into the chute while the first is 50 being mixed. After the first batch has been dumped and the drum has been brought to again revolve in the "mixing" direction, the gate is opened and the second batch permitted to slide into the drum.

The length of the trough 38 will depend upon the character of the work, its length varying indirectly as the amount of water used. First mixing dry then mixing wet forms ideal concrete. The type of drum 60 mixer shown is not adapted for wet mixing while the screw mixer is especially adapted thereto.

Having now explained my improvements, what I claim as my invention and desire to 65 secure by Letters Patent is,—

1. In a mixing machine, the combination of heads, means to revolubly support the same, spiral buckets connecting said heads and provided with interior flanges at their 70 inner ends, the buckets being formed of pairs of flat plates and joined at the central plane of the mixing machine so as to form pyramidal parts united at their bases, and means to support the mixer.

2. In a mixing machine, the combination of heads, means to revolve the same, spiral buckets connecting said heads and provided with interior flanges at their inner ends, the buckets being in halves joined at the central 80 plane of the mixing machine so as to form pyramidal parts united at their bases, and means to support the mixer.

3. In a mixing machine, the combination of heads, means to revolve the same, spiral 85 buckets connecting said heads, said buckets being in the form of pyramidal halves united at their bases, and means to support the mixer.

In testimony whereof I have signed this 90 application in the presence of two subscribing witnesses.

FRANK A. BORST.
